PULSE-TIME DEMODULATOR

Harold Goldberg, Towson, Md., assignor to
Bendix Aviation Corporation, Towson, Md., a
corporation of Delaware

Application February 27, 1947, Serial No. 731,197

6 Claims. (Cl. 250—27)

1

This invention is directed to pulse-time demodulators. More specifically it is directed to an arrangement for detecting the intelligence transmitted on a pulse-time modulated carrier.

In the reception of pulse-time modulated signals of the type having a pulse of width δ and a spacing representing successive solutions of the equation $f(t) + V - Ee^{-t/RC} = -K$, difficulty has arisen in attempting to produce a distortionless scheme.

It is an object of this invention to provide a pulse-time demodulator for waves of the character described without the introduction of distortion products in the output signal.

In the drawing:

Fig. 1 is a schematic diagram of a circuit embodying the invention; and,

Fig. 2 is a graph comprising a family of related curves illustrating voltage conditions existing at various points in the circuit of Fig. 1 during the operation thereof.

Referring now to the drawing, there is illustrated a source 10 of positive pulse signals coupled to the control electrode 11 of a vacuum tube 12 through a condenser 13. The electrode 11 is connected to the grounded cathode 14 through a resistor 15 and a bias battery 16. The battery is so poled as to maintain the tube 12 in a non-conducting state between pulses of the source 10. The anode 17 of the tube 12 is connected through a resistor 18 to a source of positive voltage indicated +B, to the control electrode 19 of a tube 20, and through a condenser 21 to ground. The anode 22 of the tube 20 is directly connected to a source of positive voltage +B. The cathode 23 of the tube 20 is connected to ground through a parallel circuit comprising a condenser 24 and a resistor 25. Circuit connections are provided from the cathode 23 to the cathode 26 of a tube 27 and to the anode 28 of a tube 29. The anode 30 of the tube 27 and the cathode 31 of the tube 29 are connected together, and thence to the control electrode 32 of a tube 33. The cathode 34 of the tube 33 is connected to ground through a resistor 35 and the control electrode 32 thereof is connected to ground through a condenser 36. A pair of terminals 37 are operatively associated with the ends of the resistor 35.

The control electrodes 38 and 39 of the tubes 27 and 29, respectively, are tied together, and, 50 thence, through a resistor 40 to the source 10 of pulse signals.

In considering the operation of the above-described arrangement the state of affairs immediately after the end of a pulse, of length δ , from 55

2

the source 10 will be described. In this connection, consideration will be facilitated by reference to the curves of Fig. 2, of which A depicts a train of input pulses 50 to 55, derived from the source 10, B shows the voltage conditions across condenser 21, C illustrates those across the parallel combination of 24 and 25 and D shows the voltage at the terminals 37. By way of example, consider the conditions existing at the end of pulse 10 50. The condenser 21, which discharged through the anode-cathode circuit of the tube 12 during the pulse, is being charged exponentially from the source +B, through the resistor 18, to a relatively high positive potential as indicated at 60. Due 15 to the positive voltage on its control electrode, the cathode follower tube 20 is conductive, and the voltage across the parallel circuit 24, 25 is rising, as shown at 70, and following, by cathode-follower action, the voltage across the condenser 21. 20 The tubes 27 and 29, which comprise a bi-directional switch are non-conductive, and the voltage across the condenser 36, and consequently the voltage across the output terminals 37, is held at a relatively constant value, as illustrated at 25 80. This constant value is approximately equal to the voltage which was present across the condenser 24 at the instant of the start of the previous input pulse, as will be explained hereinbelow.

30 At the instant of a pulse from the source 10 the tube 12 becomes conductive and the condenser 21 discharges through the anode-cathode path thereof as indicated at 61. Due to the comparatively large time constant of the parallel circuit comprising the condenser 24 and the resistor 25 the voltage across the condenser 24 decreases comparatively slowly as shown at 71, and, as it starts to decrease, the bi-directional switch comprising the tubes 27 and 29 becomes conductive due to the positive pulse applied to the control electrodes 38 and 39. The point at which this occurs is indicated at 72 on curve C. At this juncture the condenser 36 is effectively connected in parallel with the condenser 24 and assumes a voltage across its terminals equal to the voltage across condenser 24. The large time constant of the combination 24, 25 and the resulting decreased slope of the line 71 permits more accurate regulation of the voltage level applied to the condenser 36. By cathode follower action this voltage appears at the output terminals and constitutes the output signal. At the conclusion of the pulse from the source 10 the bi-directional switch 40 opens and the voltage at the output terminals 45 55 opens and the voltage at the output terminals

remains substantially constant until the next pulse.

It will be seen, therefore, that the signal at the output terminals comprises a step function which is a close approximation to the original modulation, and depends solely on the spacing between the input pulses. The train of pulses shown in curve A of Fig. 2 are modulated by an abrupt change in their repetition period which follows pulse 52. This modulation is accurately recovered in the amplitude excursions of the voltage across terminals 37 as indicated in the curve D. It will be noted that the decrease of repetition period following the pulse 52 is reflected in the curve D by the abrupt voltage drop at 81 to the new level 82 corresponding to the reduction in period. In order to properly demodulate pulses having a spacing which represents successive solutions of the equation $f(t) + V - Ee^{-t/RC} = -K$ it is necessary that the time constant of the resistor 18 and the condenser 21 be equal to the value of RC which is involved in those solutions.

What is claimed is:

1. In combination, a source of energy pulses modulated in repetition period; a saw tooth wave generating and shaping means responsive thereto; an energy storage circuit; and means momentarily applying the output of said generating and shaping means to said energy storage circuit near the peak of each of the saw tooth excursions of said output.

2. In combination, a source of energy pulses modulated in repetition period; means generating a saw tooth wave form, the amplitude of the excursions of which is a function of the modulation of said pulse period; means operating on said wave form to decrease the slope of the trailing edges of said excursions; an energy storage circuit; and means clamping said energy storage circuit to said slope changing means during each of said pulses.

3. In combination, a source of energy pulses modulated in repetition period; a saw tooth wave generator excited by said pulses; means operating on the output of said generator to decrease the slope of the trailing edges of the saw tooth excursions thereof; an energy storage circuit; and means actuated by said pulses to momentarily connect said energy storage means to said slope changing means during each of said pulses.

4. In combination, a source of energy pulses modulated in repetition period; means generating a saw tooth wave form, the amplitude of the excursions of which is a function of the modula-

tion of said pulse period; means operating on said wave form to decrease the slope of the trailing edges of said excursions; an energy storage circuit; and means actuated by said pulses to momentarily connect said energy storage circuit to said slope changing means during each of said pulses.

5. In combination, a source of energy pulses modulated in repetition period; means generating a saw tooth wave form, the amplitude of the excursions of which is a function of the modulation of said pulse period; means operating on said wave form to decrease the slope of the trailing edges of said excursions; an energy storage circuit; means connecting said energy storage circuit to said slope changing means, said connecting means including an electronic switch, said switch normally interrupting said connecting means; and means applying said pulses to said switch, whereby said connecting means is momentarily completed during each of said pulses.

6. In combination, a condenser; a charging circuit for said condenser including a source of unidirectional energy and an impedance; a discharge circuit for said condenser including the space discharge path of a normally non-conducting electron tube; a source of energy pulses modulated in repetition period; means impressing said pulses upon said tube to render it conductive during each of said pulses; a cathode follower circuit including an electron discharge tube having an anode, a cathode and a control grid; means impressing the voltage across said condenser upon said control grid; a condenser and an impedance connected in parallel in the circuit of said cathode, the time constant of said parallel combination being greater than that of the first mentioned condenser and its discharge circuit; an energy storage circuit; and means clamping said energy storage circuit to said parallel combination during each of said pulses.
